(57) **CLAIM**

I claim the ornamental design for a dashboard mount for an electronic device, as shown and described.

DESCRIPTION

FIG. 1 is a plan view of the top of the dashboard mount for an electronic device

FIG. 2 is an elevation view of the front of the dashboard mount for an electronic device

FIG. 3 is an elevation view of right side of the dashboard mount for an electronic device; and,

FIG. 4 is an isometric view, from the front right of the dashboard mount for an electronic device.
